Gustav Adolf Schettler, Leeds, England, assignor
to The Turner Tanning Machinery Company,
Portland, Maine, a corporation of Maine

Application December 12, 1930, Serial No. 501,899,
and in Great Britain December 14, 1929

3 Claims. (Cl. 24—84)

This invention relates to clips or clamping devices. The invention is illustrated as embodied in clips for use in stretching operations upon hides, skins, leather, and other similar pieces of work and for securing the articles, after being stretched, to a stretching frame or other similar support. It is to be understood, however, that the invention and various important features thereof may have other applications and uses.

- 10 As heretofore constructed, clips or clamping devices for use in stretching and securing pieces of leather to stretching frames have, almost invariably, been expensive to manufacture because of the number of parts making up the clip or 15 clamping device. Furthermore, such clips or clamping devices of the past have been difficult to operate effectively with one hand. This is a serious objection since, in the stretching of leather to secure the best results, one hand should be free to 20 position and stretch the leather while the other hand operates the clip in attaching it to the piece of leather and subsequently in stretching the leather by means of the clip. Again, at the termination of the stretching operation, the clips 25 should be readily operable to secure the leather in its stretched condition by engaging some portion of the clip with the stretcher frame. With 30 clips of prior constructions the operator has frequently experienced considerable difficulty in operating the clip and in attaching it to the leather, and in many cases even more difficulty in removing the clip from the leather preliminarily to stretching a second piece of leather after the first has 35 dried on the stretcher frame. It will be readily understood that a clip which requires unnecessary time and effort in its application to the work, or in its removal from the work prolongs the operations of stretching pieces of leather and renders the operations so costly that little or no advantage is presented over the old-fashioned method 40 of securing the pieces of leather to the stretcher frames by tacks or other driven fastenings.

In view of the foregoing, it is an object of this invention to provide a clip for use in the stretching of leather which will be simple and durable in construction and at the same time highly efficient in operation.

To these ends and in accordance with an important feature of the invention, the illustrated 50 embodiments of the invention provide a clip comprising a movable work engaging member having a thumb piece so located that it may be operated with the greatest ease by simply pressing downwardly and only slightly backwardly in accordance 55 with the natural bending movement of the

thumb of the hand which holds the clip. Since the movable work engaging member may be so readily moved to retracted position to permit engagement of the clip with the edge of the work, the engagement of the clip is facilitated to such an extent that the required number of clips may be attached to a given piece of leather with the minimum expenditure of time and effort. Furthermore, a similar retractive movement of the thumb piece disengages the clip from the leather after 60 the latter has been dried on a stretching frame.

In the illustrated constructions, the clip has a relatively broad clamping surface for engaging the finished surface of the work, with which there co-operates a movable work engaging member 70 having a thumb piece which is offset and located in juxtaposition to a narrow portion of the clip where it is freely accessible and may be readily engaged by the thumb of the hand holding the clip, the thumb piece being not only offset but 75 also bent forwardly so that the first part of its retractive movement is largely in a downward direction, thus facilitating its operation by the thumb of the hand holding the clip.

Conveniently, the clip may be provided with a 80 pin or other penetrating projection for engagement with the relatively soft wood of the ordinary wooden stretcher frames. Where the clip is provided with a pin or other sharp projection by which the clip may be secured to a wooden frame 85 in leather stretching position, another portion of the clip may be provided with one or more sharp projections, spaced from the pin, for engaging the wooden frame to assist the operator in holding the clip in leather stretching position, the clip 90 turning on the auxiliary projection or projections as on a fulcrum while the pin is being forced into the wood by downward pressure exerted by the hand that holds the clip.

These and other features of the invention and 95 novel combinations of parts will now be described in detail and then pointed out more particularly in the appended claims.

In the drawing,

Fig. 1 is a view in side elevation of the clip 100 showing one embodiment of the invention;

Fig. 2 is a plan view of the clip from above;

Fig. 3 is a view of the clip shown in Fig. 1 looking from the left in said figure;

Fig. 4 is a view similar to Fig. 1 but showing 105 a modification of the means for attaching the clip to the stretcher frame;

Fig. 5 is a view in side elevation of a special mounting for the clip; and

Figs. 6 and 7 are details of a modification of 110

the device shown in Fig. 5, illustrating the manner in which a clip grips the edges of a slot in a plate.

In the illustrated embodiment of the invention, which is designed specially as a clip for securing pieces of leather to stretcher frames, the said clip comprises a body 2 of a narrow or slender form bifurcated to form opposing limbs 4 and 6, the upper one of which has lateral extensions or projections at the front end to form a fixed jaw 8. On the other limb 6 there is a movable jaw in the form of a single-armed lever 10 mounted thereon. The limb 6 also may have lateral extensions 12 at the front end to form a foot for cooperation with other lateral extensions 13 to prevent the clip or gripping device from tilting over sideways under the pull of the material when in use.

The movable jaw or lever 10 is a work-engaging member mounted on the limb 6 opposite to the fixed jaw 8 so that a cam-like work-gripping portion 14 of the lever 10 is located in the bifurcation. As shown, the lever 10 has also a laterally offset portion 16 on which a thumb piece 18 is formed. The offset portion 16 extends from the gripping portion 14 below and behind one of the lateral extensions of the fixed jaw 8 so that the thumb piece 18 is situated in close proximity to the narrower body portion 2 on the desired side, right or left, as shown best in Figures 2 and 3.

Preferably and as shown, the movable jaw or lever 10 is in the form of a substantially S-shaped lever having a pivot 19, at or near one end on the limb 6 of the body 2, and constructed so as to extend across the body to the opposite limb 4 as clearly shown in Figure 1. That is to say, the lever 10 comprises the bent work-gripping portion 14 formed eccentrically with respect to the pivot 19 for co-operation with the fixed jaw 8, and a portion 22 bent in the reverse direction and also laterally offset as at 16 with respect to the median line of the eccentric portion, the extremity of this portion being shaped to serve as the thumb piece 18. The front lower end of the lever 10 is formed with a pair of lugs 24 to receive the pivot pin 19 whereby the lever is connected to the body 2 of the clip, the limb 6 of the body being furnished with a boss 26 which is embraced by the lugs 24 and has the pivot pin 19 passed therethrough. The pivot pin 19 is constituted by a rivet, although any other suitable form of pivotal connection may be adopted. Thus, in the complete clip, the thumb piece 18 is situated behind the fixed jaw 8, to the right or to the left of the body 2, and in close proximity thereto.

The lever 10 is controlled by a spring 28 whereby the cam-like or eccentric portion 14 is urged towards the fixed jaw 8. Conveniently, the spring 28 is a torsion spring mounted on the aforesaid boss 26 with its ends respectively in engagement with the lever 10 and the limb 6 of the frame or body 2.

The portion 14 of the lever has transverse serrations or teeth to enhance its grip, and by reason of the cam-like or eccentric formation, the grip of the lever increases as the tension on the material increases when the clip is in use.

The frame or body 2 is provided with a finger ring 30 and with a hook 32 (Fig. 1) preferably at or near the rear end as shown, for engagement with a reticulated or perforated stretching frame (not shown).

When the stretcher frame is made of an as-

sembly of soft wood boards in the manner old and well known in the industry, the body 2 of the clip will be provided with a pin or other penetrating projection 34 (Fig. 4). It will be readily understood that at the end of the stretching operation the pin 34 may be forced into the soft wood of the stretcher frame to hold the clip in leather stretching position. Preferably, and as shown, the forward end of the body member 2 is provided with a plurality of sharp projections 36 relatively much shorter than the projection 34 for engaging with the board stretcher frame to assist the operator in holding the clip and the leather in stretched condition until he can force the pin 34 into holding position in the wood on the stretcher frame.

The frame or body 2 of the clip and the lever 10 are preferably in the form of die castings although they may be made of any other suitable material, and in any other suitable manner.

Upon referring to Fig. 5 of the drawing, it will be observed that this modified clip is provided with a special mounting comprising a bar 40 mounted at its opposite ends fixedly in brackets 42 and 44. One of these brackets, in the present instance bracket 42, is secured to one of the side or end boards 46 of a stretcher frame by means of a fastener 48, the fastener 48 and the opening through which it passes in the bracket 42 being circular so that the mounting, comprising the bar 40 and the brackets 42 and 44, may revolve around the fastener 48 as a pivot, since the bracket 44 is not fastened to the stretcher frame. In this way the clip with its mounting is rendered self-adjusting to a pull in any direction upon a piece of leather. Even if the clip is not properly directed at the time that it is clamped on the work, it will at once adjust itself to the direction of pull of the work through swinging of the clip and its mounting about the pin 48.

Another purpose of the bar 40 is to permit the clip to be moved freely in a direction to stretch the leather and, at the same time, provide means instantaneously operable for holding the clip in leather stretching position.

In order to secure the clip upon the bar 40 in its adjusted position, the clip is provided with a sleeve 50 at its forward end which is rigid with the body 2 of the clip. The sleeve is perforated for reception of the bar 40 and, in addition, is provided with gripping portions at 52 and 54 which operate to grip the bar 40 to lock the clip on the bar. This gripping or locking takes place instantaneously upon release of the clip. Since the pull on the clip, due to the strain exerted by the work, is located considerably above the sleeve 50, the clip tilts upwardly at its finger end when released by the operator, and in so doing the portions 52 and 54 are caused to engage the bar 40. In order to release the clip it is necessary merely to move the rear or finger-hold end of the clip downwardly toward the bar 40, since by this action the gripping portions 52, 54 in the sleeve 50 are moved away from the bar 40.

In Figs. 6 and 7 of the drawing there is shown a modification of the means for mounting the clip on a stretcher frame. In place of the bar 40 shown in Fig. 5 there is provided a support comprising a metal plate 60 having a slot at 62. For engaging in the slot 62 of the support 60 each clip is provided with a shank portion 64 (Fig. 6) which has a thickness dimension corresponding substantially to the width of the slot. At each end of the shank portion are located laterally extending flanges 66 and 68 whereby the clip is

held with its shank portion 64 in the slot 62. At the front edges of the upper flanges 68 on each side of the slot there are portions 70 which will bite into the surface of the support 60 when the 5 clip is tipped upwardly at its rear end due to the strain of the stretched leather pulling on the front end of the clip considerably above the points of engagement of the clip with the support 60. The flanges 66 have corresponding sharp edge 10 portions 72 facing rearwardly and designed to bite into the lower surface of the support 60 on each side of the slot 62 upon the same tipping movement of the clip. It will be obvious then, that the clip is slideable on its support 60 through 15 engagement of its shank piece 64 in the slot 62 and that the clip is instantaneously set in adjusted position upon release of the clip by the operator at the termination of the retractive movement of the clip along the slot 62. The advantage 20 of the support 60 over the clip support 40 of Fig. 5 resides in the fact that a plate may have a large number of suitably directed slots along which clips may be movable, one in each slot, to effect stretching operations on a piece of leather. Clearly, as in the structure shown in 25 Fig. 5, the clips remain with the stretcher frame without possibility of displacement so that they are always accessible for leather stretching operations.

30 In using the clip shown in the drawing, the operator holds it with the fingers of one hand, the first or the second finger being introduced through the finger hold 30, and the thumb being positioned above the thumb piece 18. Upon depressing the thumb piece 18, the work engaging member 10 is lowered so that the work may be introduced between the upper work engaging member 8 and the convex roughened surface 14 on the member 10. Upon releasing the thumb 35 piece 18, the work is gripped, and upon pulling on the clip to stretch the work the gripping is rendered more effective than before. If the stretcher frame for the piece of leather comprises a perforated plate or a woven mesh of wire, a 40 hook like that shown at 32 in Fig. 1 is utilized to secure the clip in leather stretching position. If the stretcher frame be made of soft-wood boards, a clip of the type shown in Fig. 4 is employed in stretching operations, since this clip 45 comprises a pin which may be pressed into the wooden board to hold the clip in leather stretching position. If desired the type of clip shown in Figs. 5 or 6 may be employed, in which case the clip secures itself instantaneously to its 50 mounting upon release of the clip. The clip of any one of the types shown may be released from the leather simply by depressing the work engaging member 10 by pushing downwardly upon the thumb piece 18.

70

75

Having described my invention, what I claim as new and desire to secure by Letters Patent of the United States is:

1. In a clip, a body member having a relatively broad work engaging portion at one end and a finger hold at its other end, the intermediate portion of the body member being relatively narrow when compared with the work engaging portion, and a movable work engaging member fitted to the body member and having a portion for pressing a piece of work against the work engaging portion of the body member, said work engaging member having a thumb piece and a portion laterally offset to position the thumb piece in close juxtaposition to a lateral surface of the narrow portion of the body of the clip where it may be readily engaged by the thumb of the hand holding the clip. 80

2. In a clip, a body member having a relatively broad work engaging portion at one end and a finger hold at its other end, the intermediate portion of the body member being relatively narrow when compared with the work engaging portion, and a movable work engaging member fitted to the body member and having a portion for pressing a piece of work against the work engaging portion of the body member, said work engaging member having a thumb piece and a portion laterally offset to position the thumb piece in close juxtaposition to a lateral surface of the narrow portion of the body of the clip where it may be readily engaged by the thumb of the hand holding the clip. 90

95

3. In a clip, a body member having a work engaging portion at one end and a finger hold at its other end, and a movable work engaging member having a surface for co-operation with the work engaging surface of the body member in gripping a piece of work, said movable work engaging member having a thumb piece by which the work engaging member may be retracted to facilitate engagement of the work by the clip, 100 and said body member having a wood penetrating projection extending downwardly and forwardly from the body member from a point adjacent to the finger hold for holding the clip in leather stretching position on a stretcher frame, and 105 also another projection or projections extending downwardly from the body member adjacent to the other end of the body member to serve as temporary holding means for the clip when in engagement with the stretcher frame until the 110 projection adjacent to the finger hold is firmly engaged with the stretcher frame. 115
